UNITED STATES PATENT OFFICE.

ASHTON B. KIERSTEAD, OF ROCKLAND, MASSACHUSETTS, ASSIGNOR TO KIERSTEAD-ANDERSON CO., INC., OF BROCKTON, MASSACHUSETTS, A CORPORATION OF MASSACHUSETTS.

BOOT OR SHOE.

Application filed July 13, 1926. Serial No. 122,057.

The present invention relates to boots and shoes and more particularly to welted and methods of making the same.

The object of the present invention is to produce a welt which may not only be inexpensively manufactured and which will impart an ornamental effect to the shoe, but which also is useful as a means to protect against entrance of moisture between the upper and the outsole of the shoe.

With this object in view, one feature of the present invention consists in an ornamental welt having a line of fair stitching extending only partially therethrough and adapted to lie adjacent and in proximity to the upper. This welt may be used in conjunction with a Goodyear welt or a McKay shoe, the appearance in either case simulating that of a double sole shoe. The provision of a fair stitching extending partially through the welt in such a manner that a stitch is exposed in one face only makes for a smooth surface on the opposite side of the welt and therefore causes it to lie in close engagement with the usual welt or outsole of the shoe, thus effectively protecting the seams from entrance of moisture.

Another feature consists in the provision of a double layer welt having a line of stitching through one layer only, the two layers being attached together in a manner to form a pronounced bead along the line of stitching adjacent the margin of the welt. This bead is adapted to be positioned at the junction of the upper and the regular welt or outsole and it not only lends strength to the shoe, but also protects the shoe against entrance of moisture.

Other features of invention consist in certain novel features of construction and modes of operation hereinafter described and particularly defined in the claims.

In the accompanying drawings, Fig. 1 is a perspective view of the toe of a shoe embodying the welted of the present invention; Fig. 2 is a sectional view through the toe of the shoe shown in Fig. 1; Fig. 3 is a view of the inside of the welt of the present invention prior to securing of the two layers together; Fig. 4 is an outside view of the welt shown in

Fig. 3; Fig. 5 is a perspective view of the welted of Fig. 3 showing one surface after being subjected to the skiving operation and Fig. 6 is a perspective view of the completed welt.

The preferred embodiment of the invention comprises a strip of welted consisting of two layers which are cemented together, the top layer being provided with a line of stitching adjacent to the folded edge which stitching not only provides an ornamental seam at the top of the welt, but also acts as a filler to produce a bead adjacent to the margin. The bead is accentuated by reducing the thickness of one of the folds of the welt as by the skiving operation. When manufacturing a Goodyear welt shoe according to the preferred form of the invention this welt may be attached to the insole and upper of the shoe simultaneously with the regular welt.

The illustrated embodiment of the invention comprises a completed welt as shown in Fig. 6. This welt consists of a double thickness of leather or other suitable welted material having a top fold 8 and a lower fold 10 connected along the folded margin 12 and cemented together over their inner surfaces. Adjacent to the margin 12 is a line of chain stitching 14 with the chain on the inside of the welted. The chain stitching provides an increased thickness of the welt adjacent to the fold so that a pronounced bead is formed adjacent to the edge, the thickness of this bead being accentuated with respect to the thickness of the welt proper by the formation of the top fold 8 of a reduced thickness.

The welted is manufactured in the following manner: A flat strip of material shown in Figs. 3 and 4 is provided with the longitudinal chain stitch 14 which lies at one side of the longitudinal center line of the material, being positioned so that upon folding of the material the outside of the stitch will appear along the top surface of the bead. The top layer of the welt is then reduced in thickness from the line of stitching to the edge by running the welted through a skiving machine, employing the line of chain stitching as a guide. While either of the layers may be

skived, it is preferable to perform this operation on the inside surface of the layer which carries the stitching, namely the top layer of the welting. Thereafter, the two layers ⁵ are folded and cemented together to form the finished welting shown in Fig. 6.

In the manufacture of a Goodyear welt shoe, after the upper 16 has been attached to the insole 18 in the usual manner the usual ¹⁰ welt 20 of the shoe and the auxiliary welt which is indicated generally at 22 are simultaneously run in for attachment to the insole by means of a welting machine as will be obvious to those skilled in the art. The attachment ¹⁵ of the welts to the shoe is carried out by means of stitches 24 extending through both welts, the upper and the insole. Subsequently, the outsole 26 is secured to the welt 20 by stitching 28 in the usual manner. ²⁰ The finished shoe as shown in Fig. 1 presents the line of fair stitching formed by the stitches 14 at a position immediately adjacent to the upper of the shoe thus giving an ornamental effect. The bead at the fold line lies ²⁵ at the junction of the upper and the welt and by its resiliency forms a tight joint which effectively prevents entrance of water into the seams, the joint being enhanced by the fact that the line of stitching does not extend entirely ³⁰ through the welt but only through one thickness thereof so that close engagement between the auxiliary welt and the usual welt is assured.

The invention having been described, what ³⁵ is claimed is:

1. A shoe having a regular welt and a second welt with a line of exposed fair stitching adjacent to the upper of the shoe and extending partially into the said second welt, both ⁴⁰ welts being attached together to the shoe.
2. A welt comprising an integral strip having a line of fair stitching extending partially therethrough and exposed on one face only.
3. A welt comprising an integral strip having a surface for attachment to the insole of a shoe and a line of fair stitching adjacent to the edge of the welt and extending partially therethrough and exposed at one face ⁴⁵ only.
4. A welt comprising two attached layers of material having a line of fair stitching passing through one layer only, said stitching being exposed on one face of said layer ⁵⁰ and hidden on the opposite face and separating the layers.
5. A welt comprising a folded strip of material having a line of fair stitching passing through one layer only.
6. A welt comprising two attached layers of material and having a line of stitching through one layer only adjacent to the margin and separating the layers to form a bead.
7. A welt comprising a strip folded lengthwise ⁶⁰ and having a line of stitching passing

through one layer only of the strip adjacent to the folded margin of the welt and forming a filler to produce a bead at the edge of the folded strip.

8. A welt comprising two attached layers ⁷⁰ of material of different thickness and a line of stitching passing through one only of the layers adjacent to the folded margin of the welt to form a filler to produce a bead at the edge of the welt.

9. A method of making welting which consists in forming a line of stitching adjacent to the center line of a strip of material, folding the material to expose the stitching on the outer surface of one layer only, and cementing the folds together. ⁸⁰

10. A method of making welting which consists in sewing a line of stitching on one side of the longitudinal center line of a strip of material, skiving the material from the ⁸⁵ line of stitching to the nearer edge, folding the material on the center line, and cementing the folds together.

11. A welt comprising a strip folded lengthwise and having a line of chain stitching passing through one layer of the folded strip adjacent to the fold line with the chain between the layers to form a filler between the layers and to produce a bead at the folded edge of the welt. ⁹⁵

12. A welt comprising a folded strip having the folded portions cemented together, one of the portions being of less thickness than the other, and a line of stitching passing through the folded portion which is of less ¹⁰ thickness and being located adjacent the folded edge of the strip and forming a filler to produce a bead adjacent said folded edge.

13. A shoe having an upper, a sole, and a ¹⁰ welt comprising a folded strip provided with a line of fair stitching extending through one layer only of the strip and adapted to lie exposed adjacent to the upper of the shoe.

14. A shoe having an upper, a sole, and a ¹¹ welt comprising a folded strip provided with a line of fair stitching extending through one layer only of the strip and adapted to lie exposed adjacent to the upper of the shoe, and means passing through both layers of the welt adjacent their edges for securing the ¹² welt and upper together.

In testimony whereof I have signed my name to this application.

ASHTON B. KIERSTEAD.
